CARL M. GOLDBERG, OF NEW YORK, N. Y.; ASSIGNOR TO SCHAFER & GOLDBERG, A COPARTNERSHIP COMPOSED OF SAMUEL SCHAFER AND CARL M. GOLDBERG, BOTH OF NEW YORK, N. Y.

SPORT VISOR CAP.

Application filed January 13, 1927. Serial No. 160,843.

This invention relates to that type of caps which are adapted for use as eye shades or for sport wear and which are known as "visor caps" for the reason that as much 5 of the head of the wearer is left uncovered as is possible. In caps of this type it is customary to use a substantially horizontally arranged circular band to surround the head for supporting the cap. Such bands 10 are usually made narrow and are adapted to be held in place by an elastic section therein. This results in considerable pressure upon the forehead by the tensioned band which tends to prevent proper circulation of 15 the blood and leaves a red mark on the forehead. To avoid this objection, I prefer to provide a forehead piece of peculiar shape at the front of the cap for distributing the pressure on the forehead, and I prefer further to secure the forehead piece to the visor 20 through the intermediary of the front portion of said band by novel structure as will appear hereinafter.

The various objects of my invention will 25 be clear from the description which follows and from the drawings, in which,

Fig. 1 is a side view of my improved cap showing in particular my novel form of head strap.

Fig. 2 is a top plan view of the same.

Fig. 3 is a vertical central section through the front portion of the cap showing the arrangement of and the means for securing the parts in place.

Fig. 4 is a vertical section through the rear portion of the head band showing the means for securing the head strap to the head band.

Fig. 5 is an elevation of the piece of material slitted to form the head strap showing how the piece may be stretched or expanded to form the strap.

Fig. 6 is a perspective view of a modified form of my improved visor cap.

Fig. 7 is a vertical central section of the cap shown in Fig. 6 and

Fig. 8 is a vertical section through the headband of the cap shown in Fig. 6.

In the practical embodiment of my invention, I provide a continuous headband 10 which is preferably formed of two layers of material. The outer layer or strip 11 is preferably made of leather, imitation leather, or similar material, while the inner strip 12

is made of suitable light, soft fabric, or 55 similar flexible material adapted to be arranged in contact with the forehead of the wearer without discomfort. Interposed between the extremities 13 of the headband portion 10, is the elastic member 14, by 60 means of which the headband is allowed to adapt itself to fit heads of various sizes.

Referring to the modification shown in Figs. 1 to 5 inclusive, the visor 15 is arranged with the upper edge 16 thereof outside of and slightly overlapping the lower edge 17 of the headband, said edges 16 and 17 being seamed together by suitable stitching such as zig-zag overcast stitching 18 whereby the visor is secured to and conceals 70 part of the headband. The forehead member 19 is made preferably widest at the front central part thereof and is preferably shaped to taper to a point at the sides 20 thereof so that the greatest area of contact 75 thereof with the forehead of the wearer occurs at the place where the pressure on the forehead is greatest. Both the visor and forehead member are preferably made of suitable resilient, flexible and transparent 80 material such as celluloid or the like, adapted to resist the passage of light, but sufficiently transparent to allow proper vision therethrough. The edges 21 and 22 of the visor and forehead member respectively may be 85 finished or bound by means of suitable binding material as 42 covering and stitched about said edges. The forehead member is preferably inserted between the strips 11 and 12 of the headband so as to allow the 90 insertion of the head strap ends 24 outside of the forehead member and inside of the strip 11, all of the parts mentioned being then seamed together by the stitching 23 after the ends 24 of the head strap 25 have 95 been inserted in place, whereby the lower edge of the member 19 is secured between the upper edges of the strips 11 and 12. The stitching 23 is continued about the upper edges of the headband and serves to 100 secure the strips 11 and 12 in place, while the stitching 18 is similarly continued and serves the same purpose. Said ends 24 are preferably arranged at equally spaced intervals in order to properly support the cap on the head and to present a pleasing appearance.

The head strap 25 will now be described.

A preferably rectangular piece 26 of flexible material, such as leather, fabric or the like is suitably slitted to allow the expansion thereof without severance, preferably by means of a series of parallel straight slits 27, 28 and 29 arranged perpendicularly to the edges 30 and 31 in order to conserve material. The various slits are so arranged as to leave a top portion 40 of little depth entirely unmutilated, and a series of portions 41 intermediate of the edges 30 and 31 cut by alternate long slits into parts of a width substantially twice that of the distance between adjacent slits, by means of which each pair of adjacent strap members 32 are joined together. An aligned pair of slits 27 and 28 extend from a point just below the edge 31 to the bottom edge 30 with an interruption at the portion 41, whereby a pair of members 32 is formed joined at 41. It therefore becomes possible to separate adjacent strap members on each side of the slit 28 slightly, and on each side of the slit 27 to a considerable extent. Similarly a separating slit 29 is made between the adjacent pairs of slits 27 and 28, about which the major part of the adjacent members 32 may be widely separated. The lower end of the slit 29 is spaced considerably above the bottom edge 30 and ends at a point below the upper end of the slit 28 all of said slits being preferably parallel and beginning below the top edge 31. The piece 26 remains preferably unsevered at the top edge 31 thereof, so that the piece may be readily handled without the disadvantage of having a number of loose unattached ends dangling uncontrollably at the top. The distance between said slits is such as to provide strap members 32 of predetermined width throughout the major portion of the length thereof, while the ends 33 and 34 of adjacent strap members are of twice said predetermined width and the juncture of adjacent strap members 32 at points 41 intermediate at the ends thereof is substantially the same width as the ends 33 and 34. The upper ends 34 may be spread if desired by a final severing cut just before said ends are seamed to the circular finished member 35 or said ends may be left unsevered and seamed in a circle to said finished piece by suitable stitching as 36. The ends 33 after being equally spaced about the headband except at the elastic portion 14, are secured in place as hereinbefore described between the strips 11 and 12 of the headband 10 whereby the piece 26 is stretched, expanded or spaced apart in a design of pleasing appearance which design may be varied in various ways depending upon the amount of tension put on the strap members 32, upon the distances between the ends 33 and the arrangement and shapes of the various slits. In any case, I prefer to so arrange the slits that the attached por-

tions 33, 41 and 34 of adjacent strap members are alternately arranged along the length of said members, the portions 33 and 34 being substantially opposite each other.

While I have shown straight, parallel slits in the piece 26 to conserve material, it will be understood that curved, triangular or other shaped openings may be made in said piece to produce designs varying in appearance, while resulting in strap members attached to each other and capable of being spread apart to act as head supports.

In the modification shown in Fig. 6, the strap member 25 is omitted and may be replaced by a suitable head strap as 43 or a multiplicity of such straps, if desired. Since the strap ends 33 are omitted it becomes unnecessary to insert lower edge 44 of the forehead member 19 between the headband strips 11 and 12. Said edge portion 44 may therefore be placed on the outside of the headband 10 and seamed thereto by suitable stitching such as the overcast zig-zag stitching 45 in the same manner as that whereby the visor is attached to said headband.

It will be seen that the forehead member distributes the pressure of the headband over a considerable area of the wearer's forehead thereby preventing the uncomfortable effects of constriction and further shutting off any possible glare which might reach the eyes through any space between the visor end and the forehead. By connecting the forehead member to the visor through the medium of the headband, the transparent sections mentioned may be relatively manipulated when desired about the headband as a hinge. It will however, be seen that I have provided a strap of pleasing appearance which can be economically manufactured and which protects the hair of the wearer against disorder in the high winds. It will be seen finally that by reason of the peculiar construction of the headband and of the method of joining the forehead piece and visor together I have produced a simple, economical and efficient structure, well adapted for the purposes for which it is intended.

Since various modifications of the illustrated embodiment of my invention are contemplated, I do not intend to limit myself to the exact structure shown and described, but intend to avail myself of the range of equivalents afforded by the appended claims.

I claim:

1. In a visor cap, a flexible, non-elastic headband section, subtending less than a complete circle, an elastic member interposed between the ends of said section, a visor of flexible, resilient, transparent material overlapping the lower front edge of said section, a forehead member of the same material as said visor highest at the front

central portion thereof and tapering to points at the ends thereof, and in contact with said section only at the front upper edge of the latter, stitching securing said forehead member and said visor to said head-band section whereby the greater part of the outer face of said section is exposed to view, said flexible head-band section being arranged between and serving to space apart vertically the adjacent edges of said visor and said forehead member, and a head strap of a single piece of material secured at its ends to said head-band section.

2. In a visor cap, a headband formed of two narrow, thin strips of flexible, non-resilient and inelastic material, and an elastic section therein, a transparent visor entirely on the outside of, and covering the lower edge of said headband, zig-zag stitching substantially covering and securing the upper edge of said visor to said headband, and a forehead member of transparent, resilient material having its lower edge inserted between said strips and secured to said headband at the upper edge thereof and zig-zag stitching securing the lower edge of said forehead member to said headband and securing the upper edges of said headband strips together, said forehead member and said visor being vertically spaced on said head band to provide a flexible section of said headband of substantial size therebetween.

3. In a visor cap, a headband of two thicknesses of material, a forehead member and a visor each of resilient, transparent material, widest at the middle portion thereof and tapered to points at the ends thereof, stitching covering and securing the upper edge of said visor and the lower edge of said headband in overlapping relation whereby said visor overlaps the lower edge of said headband on the outside thereof and is substantially concealed by said stitching, stitching securing the lower edge of said forehead member in between the upper edges of the strips of said headband, the adjacent edges of said forehead member and said visor being arranged in vertical spaced parallel relation with a vertical headband surface therebetween, and the respective ends of said member and said visor being arranged in a substantially vertical line, and a head strap of a single piece of material having slits therein, said slits being parallel and equidistant laterally for forming strap members of predetermined width, ends on each adjacent pair of said members joined together and severed from the adjacent ends and inserted between the two thicknesses of said headband, the terminal ends of said strap being spaced apart a distance greater than that of the remaining ends, a joined portion on adjacent members of adjacent pairs of said members and a

circular end piece joining one end of each of said members in substantially circular form.

4. In a visor cap, a transparent, flexible, resilient visor, a forehead member of the same material as that of said visor and of substantially the same length as said visor arranged with its lower edge in spaced relation to and entirely above the upper edge of said visor, an automatically adjustable headband having part of the outer face at the lower edge thereof covered by the upper edge of and connecting said member and said visor and overcast zig-zag stitching securing said visor and forehead member to said headband and substantially covering the otherwise raw edges thereof.

5. In a visor cap, a transparent visor and an exposed and visible forehead member of the same material as that of said visor, each of substantially the same length, widest at the middle, pointed at the ends, and arranged in vertical spaced relation, a headband of two thicknesses of material joining said visor and member together while maintaining said visor and said member vertically apart, and a head strap having the ends thereof inserted between the two thicknesses of said headband.

6. In a visor cap, a visible and exposed forehead member widest at its middle and tapered to points at its ends and made of transparent flexible material, a narrow headband of two thicknesses of material, a multiplicity of strap members expanded from a single sheet of material having an unsevered upper end, stitching securing the lower edge of said forehead member to the upper edge of and between the two thicknesses of said headband and securing the two thicknesses of said headband together at the upper edges thereof, spaced ends on said strap members inserted between the thicknesses of said headband on the outside of and partly covering said forehead member and secured in place by said stitching, and a transparent visor partly covering the outer face and the lower edge of said headband and arranged below said forehead member with a vertical headband portion therebetween.

7. In a visor cap, a non-elastic, narrow, flexible, adjustable head-band of two thicknesses of material, an elastic section joining the ends of the said head-band, a transparent, resilient visor partly covering the outside face of and the lower edge of said head-band, a forehead member of material the same as that of said visor on the upper edge of said head-band and arranged completely above said visor with the headband therebetween, a multiplicity of strap members expanded from a single sheet of slitted material unsevered at its upper edge, spaced ends on alternate pairs of said strap members inserted between the thicknesses of said

head-band, two of said ends being arranged at the terminal portions of the inelastic part of said head-band, and some of said ends being arranged on the outside of said 5 forehead member, and stitching securing the lower edge of said head-band together and to the upper edge of said visor and securing said strap member ends in place.

8. In a visor cap, a head strap expanded 10 from a single slitted sheet, spaced lower ends on said strap, an unsevered upper end on said strap, a narrow adjustable headband secured to said ends, a transparent visor secured to the outside of and covering the 15 outer face of said headband at the lower edge thereof and a visible and exposed transparent forehead member secured to the upper edge of said headband and spaced entirely above said visor with a flexible vertical headband section therebetween.

9. In a visor cap, a head strap expanded 20 from a single slitted sheet, spaced lower ends on said strap, an unsevered upper end on said strap, a substantially circular

narrow flexible headband secured to said 25 ends, an elastic section in said headband independent of and unattached to said strap, a circular piece secured to and closing the interior space at upper end of said strap, a transparent visor and a forehead member 30 each of flexible resilient material and widest at the middle thereof and tapering to points at the ends thereof, the respective ends of said visor and said forehead member being arranged in vertical alignment, stitching securing the upper edge of said visor to the lower edge of and on the outside of said headband, and stitching securing the lower edge of said forehead member to the upper edge of 35 said headband and securing the lower ends of said head strap in place, said visor being arranged entirely below said forehead member with a section of said flexible member therebetween, whereby said forehead member and said visor may be manipulated about 40 said headband section as a hinge.

CARL M. GOLDBERG.
